US0D1065418S

(12) **United States Design Patent** (10) Patent No.: **US D1,065,418 S**
(45) Date of Patent: ** Mar. 4, 2025

(54) **FIREARM SIGHT**

(71) Applicant: **SCALARWORKS, LLC**, Easton, PA (US)

(72) Inventor: **Philippe Bartoszewicz**, South Orange, NJ (US)

(73) Assignee: **SCALARWORKS, LLC**, Easton, PA (US)

(**) Term: **15 Years**

(21) Appl. No.: **29/825,124**

(22) Filed: **Jan. 28, 2022**

(51) LOC (15) Cl. **22-01**

(52) U.S. Cl.

USPC **D22/109**

(57) **CLAIM**

The ornamental design for a firearm sight as shown and described.

DESCRIPTION

FIG. 1 is a front-left perspective view of a firearm sight;

FIG. 2 is a rear-right perspective view thereof;

FIG. 3 is a front-right perspective view thereof;

FIG. 4 is a front view thereof;

FIG. 5 is a rear view thereof;

FIG. 6 is a right view thereof;

FIG. 7 is a left view thereof;

FIG. 8 is a top view thereof; and,

FIG. 9 is a bottom view thereof.

The broken lines depict portions of the firearm sight that form no part of the claimed design.

1 Claim, 8 Drawing Sheets
